UNITED STATES PATENT OFFICE.

RALPHAL BANTLE, OF ST. LOUIS, MISSOURI.

TOY.

Application filed October 12, 1920. Serial No. 416,444.

To all whom it may concern:

Be it known that I, RALPHAL BANTLE, a citizen of the United States, residing at St. Louis, in the State of Missouri, have invented certain new and useful Improvements in Toys; and I do declare the following to be a full, clear, and exact description of the invention, such as will enable others skilled in the art to which it appertains to make and use the same.

This invention relates to improvements in toys, having more particular reference to a dancing toy embodying a plurality of movable figures mounted on a base.

The principal object of the invention is to provide a toy which is exceedingly simple in construction, very easy to operate by small children, very attractive in appearance, and comparatively inexpensive to both the manufacturer and the user.

Another object of the invention is to provide a toy of the above mentioned type wherein the operating means is concealed, this construction and arrangement permitting the peddler or salesman to demonstrate the toy to an advantage, due to the fact that it appears as if the figures are automatically operated.

A further object of the invention is to provide a toy of the above mentioned type which includes dancing or movable figures which are of such construction and mounted in such a way that they may move approximately through an entire revolution, thus permitting them to assume innumerable attractive and amusing positions with respect to each other.

Other objects and advantages of the invention will be apparent during the course of the following description.

In the accompanying drawings, forming a part of this specification and in which like numerals are employed to designate like parts throughout the same:

Figure 1 is a sectional view, partly in elevation, of a toy constructed in accordance with my invention.

Figures 2 and 3 are sections taken on the planes of the lines 2-2 and 3-3 of Fig. 1, looking in the direction of the arrows.

Briefly described, the toy comprises a hollow base having a finger inserting opening in its bottom, the dancing figures being positioned above this base and being supported and moved by a suitable means, which means is in turn operated by a concealed member

which is accessible through the openings in the bottom of the base.

Referring to the drawing wherein the preferred embodiment of my invention is clearly illustrated, it will be seen that the numeral 1 designates the hollow base which may be of any suitable construction and which is, by preference, constructed of cardboard for the purpose of reducing the cost of manufacture. This base, as above indicated, is provided in its bottom with a finger inserting opening 2 and is further provided with one or more spaced partitions 3 which are equipped with horizontally aligned guide openings 4. Rising from the base and preferably disposed near one end of the latter is a hollow metal standard 5 provided at its upper end with oppositely disposed slots 6 in which one end of an operating arm 7 is disposed, it being pivoted to the standard as indicated at 8 and normally extending laterally therefrom. Mounted on spaced pivots 9 on the arm 7 is a pair of dancing or movable figures, indicated, as a whole, by the numeral 10. These figures may be constructed from any suitable material and the body portions are, by preference, made from spaced elements 11, each of which is disposed on an opposite side of the arm 7 and carries a pivotally mounted leg 12. With this construction, it will be seen that the figures may swing on their pivots through approximately an entire revolution, thus permitting them to assume numerous positions with respect to each other, which, of course, makes the toy more novel and attractive since the figures will occupy new positions each time the arm 7 is moved.

The concealed means for imparting movement to arm 7 in its preferred form comprises a rod 13 which is slidably mounted in the guide opening 4 in the partition 3 of said base, it being so mounted that one of its ends extends into and is accessible through the finger inserting opening 2. By sliding the rod 13 with the finger, it will be seen that movement will be imparted to the arm 7 through the medium of a flexible connection 14 between member 13 and this arm. This connection is by preference extended upwardly through the standard 5 so that it, like member 13, is concealed.

In use, the base is placed in the palm of the hand and the forefinger is extended into the opening 2 in the bottom thereof in the manner indicated, the remaining fingers

gripping the opposite sides of the base. It is then obvious that by reciprocating the member 13, movement will be imparted to the arm 7 through the medium of the connection 14 and as soon as the arm 7 begins to move, the figures will automatically move about the pivots 9 and assume various positions with respect to one another, the legs thereof contacting the upper surfaces of the base and producing the desired dancing movements. While the operating rod 13 will in most cases, automatically return to a convenient position for operating, I deem it advisable to make use of a coiled spring 15 for accomplishing this result. This spring preferably surrounds the rod 13 between the partitions 3 and is secured at one end to this rod.

A careful consideration of the foregoing description taken in connection with the accompanying drawing will enable persons skilled in the art to which this invention relates to obtain a clear understanding of the same, therefore, a further description is deemed unnecessary.

Since probably the best results are obtained with the construction and arrangement herein shown, this construction and arrangement is taken as the preferred embodiment of the invention. However, I wish it to be understood that various minor changes in the shape, size and arrangement of parts may be resorted to as long as these changes do not depart from the spirit of the invention or the scope of the subjoined claims.

I claim:

1. In a toy, a hollow base having a finger inserting opening in its bottom, a hollow standard rising from the base, an arm pivoted to the standard and extending laterally therefrom, a pivotally mounted dancing figure carried by said arm, manually operable means for imparting movement to the latter, the same being concealed in the base and accessible through said finger inserting opening, and a connection between the arm and said means, extending through said standard.

2. In a toy, a hollow base having its bottom side provided with a finger inserting opening, a dancing figure positioned above the base, means for supporting and moving the figure, and a concealed manually operat-

ed slideable operating member entirely disposed in the base and having one of its ends extending above said finger inserting opening and serving to impart motion to said supporting means, when moved by a finger extending through the opening.

3. In a toy, a base, a standard rising therefrom, a manually movable arm carried by the standard, and a plurality of figures mounted on closely spaced pivots on said arm, the body of each figure being made up of spaced parts which are disposed at opposite sides thereon to permit said figures to move approximately through an entire revolution to assume innumerable positions with respect to one another.

4. In a toy, a hollow base provided with spaced partitions having aligned guide openings, an operating rod slideable through said openings, an upright rising from the base, an arm pivoted to the upright, a connection between the operating rod and arm, and a movable figure carried by the latter.

5. In a toy, a hollow base provided with a finger inserting opening and spaced partitions having aligned guide openings, an operating rod slideable through said openings, a hollow standard rising from the base and provided with aligned slots at its upper end, a laterally extending arm arranged in the slots and pivoted to the standard, a flexible connection between the inner end of said arm and the aforesaid rod, and a movable figure pivotally mounted on the arm.

6. In a toy, a hollow base provided with a finger spaced inserting opening, a hollow standard mounted on said base, an arm pivotally connected with said standard, a figure movably connected with said arm and receiving movement when the arm is moved, a concealed operating member arranged in said base and being operated through said finger-inserting opening, and a connection between said arm and operating member, being concealed in said standard and imparting movement to the arm when the operating member is moved.

In testimony whereof I have hereunto set my hand in the presence of two subscribing witnesses.

RALPH BANTLE.
